(57) **CLAIM**

The ornamental design for a main processing unit of a video communication set, substantially as shown and described.

DESCRIPTION

FIG. 1 is a perspective view of a main processing unit (hereinafter “MPU”) of a video communication set showing our new design.

FIG. 2 is a top view of the MPU of the video communication set of FIG. 1.

FIG. 3 is a bottom view of the MPU of the video communication set of FIG. 1.

FIG. 4 is a right side view of the MPU of the video communication set of FIG. 1.

FIG. 5 is a left side view of the MPU of the video communication set of FIG. 1.

FIG. 6 is a front view of the MPU of the video communication set of FIG. 1; and,

FIG. 7 is a back view of the MPU of the video communication set of FIG. 1.

The broken lines in the drawings consisting of large uniform dashes depict environment only and form no part of the claimed design; the broken lines consisting of a long dash

(Continued)

and two short dashes depict portions of the main processing unit of a video communication set that form no part of the claim.

1 Claim, 3 Drawing Sheets

Related U.S. Application Data

division of application No. 29/518,645, filed on Feb. 25, 2015, now Pat. No. Des. 759,621.
